United States Patent Office

Des. 179,449
Patented Dec. 25, 1956

179,449

BALL POINT PEN

Robert J. Harper, Scarsdale, and Robert H. Ensign,
Bronxville, N. Y., assignors to Scripto, Inc., a corpora-
tion of Georgia

Application October 14, 1955, Serial No. 38,369

Term of patent 14 years

(Cl. D74—17)

Fig. 1

Fig. 2

Fig. 3

Fig. 4

Fig. 1 is a front elevational view of a ball point pen showing our new design;

Fig. 2 is a side elevational view of the ball point pen shown in Fig. 1;

Fig. 3 is a top plan view thereof; and

Fig. 4 is a bottom view thereof.

We claim:

The ornamental design for a ball point pen, as shown.
